UNITED STATES PATENT OFFICE.

GEORGE W. MABIE, OF BROOKLYN, NEW YORK.

DESIGN FOR A PEN-HOLDER.

SPECIFICATION forming part of Design No. 20,040, dated July 15, 1890.

Application filed May 16, 1890. Serial No. 352,093. Term of patent 7 years.

To all whom it may concern:

Be it known that I, GEORGE W. MABIE, a citizen of the United States, and a resident of Brooklyn, in the county of Kings and State 5 of New York, have invented and produced a new and original Design for Pen-Holders, of which the following is a specification, reference being had to the accompanying drawings, forming a part thereof, and representing 10 a longitudinal view of a pen-holder of my design.

My design consists in the configuration hereinafter described of the socket portion 15 of the holder, which is reduced in size as compared with the stock or handle.

A designates the socket, and B the stock or

handle. The socket is smaller in circumference than the stock or handle, and a shoulder *a* is formed at the junction. The socket is of substantially cylindrical form externally, presenting a narrow smooth annular portion *c* at the extremity, a wider smooth annular portion *b* next the shoulder *a*, and an intermediate circumferential portion *d*. 20

What I claim as my invention, and desire 25 to secure by Letters Patent, is—

The design for a pen-holder, substantially as herein shown and described.

GEO. W. MABIE.
